Term of patent 3½ years

(Cl. D47—7)

To all whom it may concern:

Be it known that we, Robert D. Blum, Jr., and Shepard B. Schwartz, citizens of the United States of America, residing at Nashville, in the county of Davidson and State of Tennessee, have invented a new, original, and ornamental Design for a Sock or Similar Article, of which the following is a specification, reference being had to the accompanying drawing, forming a part thereof, wherein the figure is a side elevation of a sock or similar article, illustrating our new design.

The design shown in the drawing is applied to both sides of the sock or similar article.

We claim:

The ornamental design for a sock or similar article, as shown and described.

ROBERT D. BLUM, JR.
SHEPARD B. SCHWARTZ.
